(57) **CLAIM**

The ornamental design for a folding dry erase board, as shown and described.

DESCRIPTION

FIG. 1 is an isometric view of a folding dry erase board according to the present invention in an open position;

FIG. 2 is a front view of the folding dry erase board illustrated in FIG. 1;

FIG. 3 is a back view of the folding dry erase board illustrated in FIG. 1;

FIG. 4 is a left side view of the folding dry erase board illustrated in FIG. 1, the right side view being a mirror image thereof;

FIG. 5 is a bottom view of the folding dry erase board illustrated in FIG. 1;

FIG. 6 is an inverted top view of the folding dry erase board illustrated in FIG. 1; and,

FIG. 7 is an isometric view of the folding dry erase board according to the present invention in a closed position.

The structure depicted by means of broken lines in the figures has been shown for illustrative purposes only and forms no part of the claimed design.
